UNITED STATES PATENT OFFICE

CLARENCE WRIGHT, OF RACINE, WISCONSIN, ASSIGNOR TO WRIGHT RUBBER PRODUCTS COMPANY, OF RACINE, WISCONSIN, A CORPORATION OF WISCONSIN

PAVEMENT

Application filed July 25, 1924, Serial No. 728,192.

This invention relates to a pavement and a method of making the same.

The pavement to which the invention applies has a concrete base upon which paving blocks are arranged.

The invention has for its object to provide a durable and efficient pavement.

Another object is to provide a pavement having a concrete base to which the paving blocks may be readily fastened.

According to the invention, the concrete base, which contains coarse aggregate, is provided with sections containing only fine aggregate and the paving blocks arranged upon 15 the base are secured thereto by fasteners passing into the fine aggregate sections.

The invention is ordinarily employed for paving streets, roadways, floors and the like.

A pavement constructed in accordance with 20 the invention is shown in the accompanying drawing in which the views are as follows:

Fig. 1 is a vertical section.

Fig. 2 is a plan view.

A corrugated reinforcement 1 of foraminous material, such as expanded metal, is embedded in the concrete base 2 and strengthens the same.

The tops of the narrow corrugations or 30 pockets 3 are arranged substantially flush with the top of the base 2.

The foraminous sides and tops of the pockets 3 permit the fine aggregate to enter but exclude the coarse aggregate.

The base 2 thus has narrow strips or rows 35 containing fine aggregate only and surrounded by coarse aggregate.

After the concrete has set, the paving blocks may be applied thereto.

The base is ordinarily covered by rubber 40 paving blocks 4, such as disclosed in Reissue Patent No. 16,867, reissued February 7, 1928, but other blocks may be employed.

A waterproof coating, such as rubber cement, may be applied between the blocks and 45 the concrete to prevent deterioration of the concrete by moisture.

The blocks 4 are so arranged upon the base 2 that the flanges 5 thereof are in alinement with the pockets 3.

Fasteners 6, such as ordinary driving

screws, are driven through the flanges 5 and into the concrete in the pockets 3.

The blocks 4 are provided with recesses which are complementary to and receive the flanges 5 on the adjoining blocks so that the 55 tops 7 of the blocks form a continuous smooth surface.

The individual blocks are thus interlocked with the adjoining blocks and the fasteners 6 are protected against damage by traffic and 60 the elements.

The invention herein set forth is susceptible of various modifications and adaptations without departing from the scope thereof as 65 hereafter claimed.

The invention is hereby claimed as follows:

1. A pavement comprising a base having portions of fine and coarse aggregate substantially flush with the surface, and paving blocks secured to said portions of fine aggregate by fastening means passing from the blocks into said portions.

2. A pavement comprising a base having portions of fine and coarse aggregate substantially flush with the surface, paving blocks thereon, and screws passing through portions of said blocks and into said portions of fine aggregate.

3. A pavement comprising a base having corrugated reinforcing members laid therein so as to form portions of fine aggregate beneath the upper corrugations which are substantially flush with the surface of the base, and paving blocks secured to said portions of fine aggregate.

4. A pavement, comprising, a foraminous sheet shaped to provide depending and upstanding pockets arranged side by side, concrete arranged in said depending and upstanding pockets and paving blocks arranged upon the concrete in said depending pockets and fastened to the concrete in said upstanding pockets.

5. A pavement, comprising, a foraminous sheet shaped to provide depending and upstanding pockets arranged side by side and having a mesh to allow relatively fine aggregate to pass through the same, coarse aggregate arranged in said depending pockets, fine 100

aggregate arranged in said upstanding pockets, and paving blocks arranged upon said coarse aggregate and fastened to said fine aggregate.

5 6. A pavement, comprising, a foraminous sheet shaped to provide depending and upstanding pockets arranged side by side, concrete arranged in said pockets and having said sheet embedded therein, and paving 10 blocks arranged upon the concrete in said depending pockets and fastened to the concrete in said upstanding pockets.

15 7. A pavement, comprising, a foraminous sheet shaped to provide depending and upstanding pockets arranged side by side, fine aggregate arranged underneath said sheet and having said sheet in continuous contact therewith, coarse aggregate arranged in said depending pockets, and paving blocks arranged 20 upon said coarse aggregate and fastened to said fine aggregate.

25 8. A pavement, comprising, a foraminous sheet shaped to provide depending and upstanding pockets arranged side by side and having a mesh to allow fine aggregate to pass through said sheet and to exclude coarse aggregate from passing therethrough, fine aggregate arranged underneath said sheet and having said sheet in continuous contact therewith, coarse aggregate arranged in said depending pockets, and paving blocks arranged upon said coarse aggregate and fastened to said fine aggregate.

30 9. A pavement, comprising, coarse aggregate, fine aggregate arranged in pockets in said coarse aggregate, and paving blocks arranged upon said coarse aggregate and fastened to said fine aggregate.

35 10. A paving block, comprising, a coarse aggregate, fine aggregate arranged in pockets in said coarse aggregate, and paving blocks arranged upon said coarse aggregate and fastened to said fine aggregate.

40 11. A paving block, comprising, coarse aggregate, fine aggregate arranged in pockets in said coarse aggregate, a foraminous sheet arranged between said coarse and fine aggregate and embedded between the same, paving blocks arranged upon said coarse aggregate 45 and fastened to said fine aggregate.

50 12. A paving making process in which a foraminous sheet having depending and upstanding pockets arranged side by side is placed in position, fine aggregate is passed through said sheet and underneath the same, coarse aggregate is retained in said depending pockets, and paving blocks are set upon said coarse aggregate and fastened to said fine aggregate.

55 13. A paving making process in which fine aggregate and coarse aggregate are segregated into a foundation having the fine aggregate arranged in pockets in the coarse aggregate and paving blocks are arranged upon the

coarse aggregate and fastened to the fine aggregate.

In witness whereof, I have hereunto subscribed my name.

CLARENCE WRIGHT.
